UNITED STATES PATENT OFFICE.

STRATFORD B. ALLEN, OF CAMBRIDGE, MASSACHUSETTS.

DEVICE FOR FILLING DRAWING-PENS.

1,047,873.

Specification of Letters Patent. Patented Dec. 17, 1912.

Application filed December 7, 1911. Serial No. 664,367.

To all whom it may concern:

Be it known that I, STRATFORD B. ALLEN, of Cambridge, in the county of Middlesex and State of Massachusetts, have invented 5 certain new and useful Improvements in Devices for Filling Drawing-Pens, of which the following is a specification.

This invention relates to a device for filling drawing pens.

10 The object of the invention is to provide a device by means of which a drawing pen may be quickly filled without smearing ink upon the outside of the pen.

15 A further object of the invention is to provide means for quickly cleaning the pen of dried ink.

20 A still further object is to provide a convenient supply of absorbent material to remove any ink from the outside of the pen in case some should be spilled thereon.

I will describe my invention in the following specification and point out the novel features thereof in the appended claims.

25 In the accompanying drawing, Figure 1 is a sectional elevation of the device complete showing the method of filling a ruling pen, and Fig. 2 is a plan view of the device.

30 As illustrated in the drawing the device comprises a cylindrical shell 1, preferably of metal, set into a cap 2 having a hole 3 into which a small tube 4 is inserted. The top of the shell 1 is closed by a cap 6, which fits said shell closely. The top cap 6 is provided with a filling inlet, which is closed by a 35 removable plug 8, and said cap is also provided with a screw threaded bushing 10, which forms a guide for the upper end of a valve stem or rod 12. Affixed to the lower end of the valve stem 12 is a metal disk 14, 40 which is faced on its under side with a disk of rubber or other suitable material 16 and adapted to fit the outlet 3. Depending from the lower end of the valve stem, is a wire 18 passing through the outlet 3 and discharge 45 tube 4, said wire being bent at substantially the same curvature as the tube 4. The valve disk 14 is normally pressed downward to close the outlet 3 by a coiled spring 20, which embraces the valve stem and engages the 50 disk 14 and the inner end of the bushing 10. The valve is raised from its seat by a bell-crank lever 22, fulcrumed at 24 in ears 26 projecting laterally from the top cap 6. The horizontal arm 28 of the lever 22 is 55 adapted to engage the under side of a head or button 30 on the upper end of the valve

stem 12. The lower end of the vertical arm of the lever 22 is bifurcated to form guiding fingers 32, for guiding the pen 34 as it is placed in filling position, the junction of 60 said fingers being slightly above and in line with the discharge end of the tube 4.

The ink reservoir, composed of the cylinder 1 and caps 2 and 6, is mounted on a base 36, which is preferably made of metal, and 65 is cut away on one side to allow the nibs of the pen to be brought under the filling tube 4.

The filling device is operated as follows:— The drawing pen is grasped in one hand and inserted in the guide 32, with the discharge 70 end of the tube 4 between the nibs of the pen. Then the pen is pressed inward, and with it the lower end of the lever 22, thereby raising the arm 28 of said lever. The arm 28 engages the button 30 on the valve stem and 75 raises the latter, and with it the disks 14 and 16 are raised from the valve seat. Thus the outlet 3 and tube 4 are opened, and the ink is permitted to flow therethrough into the space between the nibs of the pen 34, 80 which is then filled with the amount desired. In withdrawing the pen the lever 22 is released and the parts are restored to normal position with the flow of ink cut off. The wire 18 depending from the lower end 85 of the valve stem moves back and forth through the discharge tube to maintain a free passage for the ink, and breaks up any obstruction formed by the drying up and consequent hardening of exposed ink at the 90 discharge end of said tube.

The pen cleaner is composed of two strips of metal 40, 41, which may conveniently be secured to the wall of the cylinder 1, and are bent to form a fork or guide for the pen. 95 A thin piece of brass or other metal 42 is held between the strips 40, 41, preferably by a screw 44. To clean the pen it is inserted between the strips 40, 41 with the metal strip 42 between the nibs, then the pen is 100 drawn upward and the strip 42 passes between the two points of the pen, forcing out any dried ink or foreign matter lodged therein.

The pen wiper is conveniently mounted on 105 the base of the device and comprises a metal tube 50 slotted through one side as at 52 and set into a socket 54 formed on the base 36, or the tube may be made with a metal bottom. The tube is filled with disks 56 of 110 blotting paper, or other suitable absorbent. The soiled pen is inserted through the slot

52 and drawn over the topmost disk to wipe the former clean. When the topmost disk becomes soiled, it is removed to expose a clean disk. The supply of disks may be replenished from time to time.

While I have illustrated and described a preferred embodiment of the invention, I am aware that many modifications can be made therein by any person skilled in the art without departing from the scope of the invention as expressed in the claims. Therefore I do not wish to be limited to all the details of construction shown and described, but

What I claim is:—

15. 1. A device for filling drawing pens, comprising an ink reservoir provided with a discharge tube, a valve for controlling the flow of ink through said discharge tube, and

a guide for the pen operatively connected to open said valve when the pen is moved 20 into filling position.

2. A device for filling drawing pens, comprising an ink reservoir provided with a discharge pipe communicating with its lower end, a valve for controlling the flow of ink 25 through said pipe, a lever connected to said valve, and a guide on said lever arranged to position the pen in correct relation with the outlet of said discharge pipe when said valve is opened.

30 In testimony whereof I have affixed my signature, in presence of two witnesses.

STRATFORD B. ALLEN.
